CLAIM

The ornamental design for a health monitoring watch, as shown and described.

DESCRIPTION

FIG. 1 is a top, frontside perspective view of a health monitoring watch.

FIG. 2 is a bottom, backside perspective view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a backside elevation view thereof.

FIG. 8 is a frontside elevation view thereof.

FIG. 9 is a cross-sectional view through the center of the health monitoring watch along line 9–9. in FIG. 6; and, FIG. 10 is a top, backside perspective view, thereof, and shown in an environment.

The broken lines are included for the purpose of illustrating portions of the health monitoring watch that form no part of the claimed design to provide context. None of the broken lines form a part of the claimed design.

1 Claim, 7 Drawing Sheets
